Primary Examiner — Sheryl Lane*Assistant Examiner* — Samantha N Wood(74) *Attorney, Agent, or Firm* — CIONCA IP Law P.C.;
Marin Cionca(57) **CLAIM**

The ornamental design for a guitar, as shown and described.

DESCRIPTION

FIG. 1 is a front elevational view of a guitar showing the new design;

FIG. 2 is a back elevational view thereof; and,

FIG. 3 is a partial bottom left side perspective view thereof. The broken lines shown in the drawings are included for the purpose of illustrating environmental structure and form no part of the claimed design.
